UNITED STATES PATENT OFFICE.

FRANK SLERKA, OF SCHUYLER, NEBRASKA.

STEAM-BOILER.

1,199,623.

Specification of Letters Patent. Patented Sept. 26, 1916.

Application filed August 3, 1914. Serial No. 854,811.

To all whom it may concern:

Be it known that I, FRANK SLERKA, a citizen of the United States, residing at Schuyler, in the county of Colfax and State of Nebraska, have invented certain new and useful Improvements in Steam-Boilers; and I do hereby declare the following to be a full, clear, and exact description of the invention, such as will enable others skilled in the art to which it appertains to make and use the same.

This invention relates to steam boilers, and one of the principal objects of the invention is to provide a boiler having an invention closed fire box adapted to receive liquid fuel sprayed against a fire brick bridge wall made of checker work, and to provide means for forcing air into the fire box, and providing means for operating a valve when there is an excessive pressure in the fire box to permit the exhaust to mix with the boiler water to increase the steam pressure.

Another object of the invention is to provide a steam boiler having means for regulating the pressure automatically and for utilizing the exhaust for running a steam turbine or dynamo to acquire the necessary air pressure for feeding the fuel into the fire box.

These and other objects may be attained by means of the construction illustrated in the accompanying drawings, in which—

Figure 1 is a longitudinal sectional view through the boiler and showing a portion of one end of the fire box broken away. Fig. 2 is a vertical sectional view taken on the line 2—2 of Fig. 1, looking in the direction indicated by the arrows, and made on a larger scale, Fig. 3 is a detail longitudinal sectional view of the exhaust valves or pistons, Fig. 4 is a detail sectional view of the exhaust tube, Fig. 5 is a longitudinal sectional view of a portion of the same, and Fig. 6 is a detail vertical sectional view of the exhaust valve or pistons operating from the upper portions of the boiler 1 and the pipe 5 extending from the air tank 4.

Referring to the drawings, the numeral 1 designates a boiler, 2 is the steam dome, and 50 3 is a safety valve. A combined fuel tank and compressed air reservoir 4 is provided with an air pipe 5 leading from the top thereof down through a vertical branch 6 and into a fire box 7, while the fuel pipe 8 55 leads from the bottom of the tank and is connected at 9 to the air pipe 6. The air in-

let valve *a*, and the oil inlet valve *b* are connected to the pipes near the mixing point.

The fire box 7 is provided with fire brick checker work 10 near the fuel inlet end, and a suitable sparking device 11 is disposed in the space 12 adjacent the checker work 10. Near the opposite end of the fire box is a valve casing 13 which communicates with the fire box and extends through an opening 65 in the boiler head. Outside the boiler is a flaring spider 14 which terminates in an extended valve casing 15. A valve stem 16 extends through the casing and is provided with a valve head 17 upon one end, and a smaller valve head 18 upon the opposite end, 70 said valve heads fitting the portions 13 and 15 of the valve casing. The air pipe 5 leads from the top of the combined fuel and compressed air tank 4 through the safety valve 3, and from thence down to the valve casing 15 where it communicates with the same at one side of the piston head 18, as shown 75 more clearly in Fig. 3.

At the bottom and preferably at one side 80 of the fire box 7 is an exhaust tube 19 which communicates with the valve casing 13 and is bent angularly and extends along the side and bottom of the fire box 7, as shown more clearly in Fig. 1. The exhaust pipe 19 is 85 provided with a series of openings 20 in the underside thereof, and connected immediately below said openings are flaring or semi-funnel shaped water inlet elements 21. The exhaust pipe 19 is open at its front end as 90 shown at 22, and said exhaust pipe is supported upon a suitable bracket 23.

The operation of the invention may be briefly described as follows:

The air pressure in the tank 4 is constantly 95 maintained at one hundred and sixty-five pounds per square inch by a pump not shown. When the boiler 1 is filled with water the valve *a* leading to the air tank is partially opened and air is admitted to the fire box 7. The fuel valve *b* is partially opened and the combined air and gas is ignited by the sparker 11, said gas and air being sprayed against the bridge wall checker work 10. As the area of its working face is greater than the area of the working face of the piston 18, the valve 17 will, when the pressure in the fire box 7 reaches one hundred and fifty-two pounds per square inch or greater, be forced outwardly to open 100 communications between the fire box and the exhaust pipe 19. The combined fuel, gas and 105 exhaust pipe 19.

air then passes through the exhaust pipe 19 and a quantity of water is carried through the semi-tubular funnels 21, the exhaust finally mixing with the water in the boiler 1. When 5 the pressure in the fire box 7 falls below one hundred and fifty-two pounds per square inch, the air pressure acts against the working face of the piston 18 and moves the valve 17 inwardly and closes the exhaust pipe 19. 10 Should the boiler pressure reach more than one hundred and fifty pounds per square inch the safety valve 3 will be operated to blow off through the outlet *d*, and it can be readily seen that should the pressure in the 15 boiler exceed 152 pounds per square inch that the pressure acting upon the working face of the valve 17^a would force the same upwardly against the pressure on its opposite face thereby opening the exhaust 20 port *d*. When the pressure in the fire box falls below 152 pounds per square inch, the air pressure coming in from the tank 4 enters through the pipe 5 and acts against the piston face 18^a closing the exhaust port *d*. As 25 the openings through the valves *a* and *b* are smaller than the diameter of the pipes 6 and 8, and as the valves are only partially opened, the pressure of the air and gas entering the combustion chamber 7 from the pipes 30 6 and 8 will be considerably less than the pressure in the reservoir 4. The exhaust may be utilized, however for operating a turbine or a dynamo for recharging the air tank. 35 What is claimed is:—

1. A steam boiler provided with an interior fire box, a combined compressed air

tank and fuel tank, pipes leading from said tanks into said fire box, a sparking device, an exhaust pipe for said fire box, a compound valve for controlling communication between the fire box and the boiler, and one of the air pipes leading from the air tank to the opposite end of the boiler and controlled by a valve. 40 45

2. In a steam boiler the combination of a combined compressed air and fuel tank, a fire box within said boiler, communication between the air and fuel tank and said fire box, an exhaust pipe located within said boiler and communicating with the fire box, a compound valve controlling the communication between the fire box and exhaust pipe, and an air pipe communicating with said tank and valve, and a valve connected to said pipe and to said boiler for permitting the excess pressure in said boiler to escape there-through automatically. 50 55

3. A steam boiler provided with an interior fire box, a combined compressed air tank and fuel tank, pipes leading from said tanks to the said fire box, a sparking device or exhaust pipe from said fire box, a compound valve for controlling the communication between the fire box and the boiler, said valve operated by the pressure from the air tank, and also operated by the pressure in the fire box. 60 65

In testimony whereof I affix my signature in presence of two witnesses.

FRANK SLERKA.
